UNITED STATES PATENT OFFICE.

HOWARD V. BRUMLEY, OF NEW YORK, N. Y., ASSIGNOR TO WHITALL, TATUM COMPANY, OF NEW YORK, N. Y., A CORPORATION OF NEW JERSEY.

BREAST-PUMP.

949,258.

Specification of Letters Patent. Patented Feb. 15, 1910.

Application filed February 23, 1909. Serial No. 479,570.

To all whom it may concern:

Be it known that I, HOWARD V. BRUMLEY, a citizen of the United States, and resident of the borough of Brooklyn, county of 5 Kings, city and State of New York, have invented certain new and useful Improvements in Breast-Pumps, of which the following is a specification.

My invention relates to breast pumps and 10 has for its object to construct a pump of this description in such a manner that the interior will be free from angles so as to be easily and thoroughly cleaned and which may be applied to the breast in any position 15 and still retain the milk against entrance to the bulb. I further attach the bulb to the neck of the receptacle in such a manner as to secure an air tight joint and consequent perfect suction.

20 My invention will be fully described hereinafter and the features of novelty will be pointed out in the appended claim.

Reference is to be had to the accompanying drawings in which—

25 Figure 1 is a part elevation and part central sectional view of my improved pump; Fig. 2 is a cross section thereof on the line 2—2 of Fig. 1; and Fig. 3 is a perspective view of the bulb.

30 In the drawings A represents the flaring mouth of the pump which is applied to the breast and which is connected and communicates with the bulbous receptacle B. The said receptacle B is formed with a screw-threaded tubular neck C adapted to receive the screw-threaded sleeve or collar D. The rubber bulb E is provided with a neck portion E' formed with an annular flange E² arranged to abut against the end of the neck

35 C. The collar D is provided with an annular flange D' loosely surrounding the neck portion E' of the rubber bulb E and adapted to engage the flange E² thereof. Thus as the collar D is screwed up on the neck C, 40 the flange E² will be firmly clamped between the end of the neck C and the flange D' of the collar D. The connection between the rubber bulb and the neck C is thus absolutely air tight and a perfect suction is 45 secured as the bulb E is operated. It will be noticed that the inner diameter of the neck portion E' is less than the inner diameter of the neck C of the receptacle. A sort of protecting rim E³ is thus formed which pre-

50 vents the contents of the bulbous receptacle from easily running into the bulb E. The bulbous receptacle B is circular or continuous in cross-section so that it is unnecessary to carefully position the pump on the breast, as no matter what the position of the pump some part of the said receptacle B will be in a depending position to receive the milk. The more the collar D is screwed up on the neck C, the better will be the connection between said neck and the rubber 55 bulb. The parts of my improved pump may be easily separated for the purpose of cleaning and owing to the interior form of the pump and the absence of angles this cleaning is easily accomplished and is thorough 60 in its results. It should be noted that the flaring mouth A of my improved pump is of such size and shape that it will always be clear of the breast nipple whether held in the hand or allowed to hang free. 70

75 I claim as my invention:

A breast pump comprising a one-piece receptacle and a collapsible suction bulb, said receptacle having a central spherical portion provided with an outwardly flared neck 80 or tubulature adapted to surround without touching the nipple joined to one side thereof, and a cylindrical neck joined to the other side thereof, both tubulature and neck having a diameter of the sphere as their central 85 axis and the neck having an external screw thread formed thereon; and the suction bulb being spherical in shape and provided with a neck having an external annular flange at the outer extremity thereof, the outer diameter of said flange being substantially equal to that of the neck of the receptacle and its internal diameter substantially less than the internal diameter of the neck of the receptacle; said receptacle and said suction bulb being clamped together with the outer ends of their two necks abutting and so held by a tubular cap provided with a screw thread to fit the threaded neck of the receptacle and an inwardly projecting flange 90 at one end to engage the flange of the suction bulb neck, as and for the purpose described. 95

In testimony whereof I have hereunto set my hand in the presence of two subscribing 100 witnesses.

HOWARD V. BRUMLEY.
